UNITED STATES PATENT OFFICE.

PAUL A. JOHNSON, OF DENVER, COLORADO.

ILLUMINATED INDICATOR.

Application filed April 28, 1923. Serial No. 635,308.

To all whom it may concern:

Be it known that I, PAUL A. JOHNSON, a citizen of the United States of America, residing at Denver, in the county of Denver and State of Colorado, have invented certain new and useful Improvements in Illuminated Indicators, of which the following is a specification.

This invention relates to means for displaying a sign or number and while particularly useful and valuable to display automobile license numbers will be found equally valuable in many other installations.

The principal object of the invention is to provide means for obtaining maximum visibility of the indication both day and night.

A further object, pertaining to the use of the invention on automobiles, is to provide identification means in addition to the license number.

A still further object is to so construct the indicating portion of the tag that it might be used singly without the illumination feature if desired.

Other objects and advantages reside in the detailed construction of the invention, which result in simplicity, economy and efficiency, and which will become more apparent from the following description.

In the following detailed description of the invention reference is had to the accompanying drawing which forms a part hereof. Like numerals refer to like parts in all views of the drawing and throughout the description.

In the drawing:—

Fig. 1 is front elevation of one form of the invention.

Fig. 2 is vertical cross section taken on the line 2—2, Fig. 1.

Fig. 3 is a detail cross sectional view of the transparent or translucent medium employed in the invention.

Fig. 4 is a front elevation of an alternate form of the invention. The shading in this view represents color.

Fig. 5 is a perspective view of an improved automobile license plate which could be adapted for use with or without the balance of the invention.

Let the numeral 10 indicate an automobile license plate, preferably black in color, the characters of which are cut out as indicated at 11. License plate 10 is furnished with an attached plate 24 of lighter material, as shown at 25. Plate 24 is white in

color and vividly outlines the cut out characters in the black plate 10. The two plates 10 and 24, when used without the other features of the invention, to be described, form a license tag of greater visibility than the ones at present in use and it has the additional advantage in that the plate 24 can be removed and the stencil plate 10 placed in a light containing box 12 for night illumination.

Box 12 comprises two sections, 13 and 14, hinged together, as shown at 15, and secured in the closed position by means of any suitable catch 16. A light bulb 17 serves to illuminate light box 12 at night. One face 18 of the box 12 is closed and the opposite face is provided with window 19 having a metallic frame 20.

The plate 10 is placed in the window 19 against the frame 20 and a translucent plate 21 is secured against the inner face of the plate 10. The translucent plate 21 is one of the principal features of the invention and its construction and principle, as applied to an application of this character, is believed to be new and novel.

Plate 21 is so constructed as to show perfectly white in the daytime, so as to throw the characters into bold relief, and brilliant red when illuminated at night. This result is obtained by having the side of the plate 21, towards the plate 10, of white translucent material and the opposite side, towards the light 17, of red translucent material. As illustrated plate 21 consists of a sheet of white translucent glass colored on the inner face with red translucent color, as shown in Fig. 3, but may be formed in many ways such as frosted glass colored on the back or by two glasses one white and one red, if desired.

In the form shown in Fig. 4, the name of the automobile carrying the device is cut out in stencil form in the frame 20 of the box 12, as indicated at 22. This name being in front of the white side of the translucent plate 21 will show white in the day time but the rear of the plate 21 is so colored at this point as to show at night a color corresponding to the color of the car carrying the plate. For instance, supposing the automobile, shown in the background of Fig. 4, at 23, is a blue Page, the name "Page" would appear at 22 in blue letters. This would serve as an additional identification at night when without it, it might be impossible to ascertain the

make or color of the car. At night the red rays of light coming through the characters of plate 10 would serve as a "tail-light" and make a separate signal unnecessary.

5 In Fig. 4 the color indications are shown as they would appear at night with the light box 12 illuminated.

A colored translucent medium, when interposed in a beam of light, has the property 10 of absorbing all light rays which are complementary to its color, thus a red medium will absorb all but the red rays corresponding to its color. Therefore, in this invention, the light transmitted to the white translucent 15 material consists wholly of red rays. White, being a combination of all colors, has no complementary color, as complementary colors are defined as those colors which combined with the given color produce white, 20 and will therefore absorb no color and allow all of the color rays to pass. The red rays will therefore pass through the white translucent material with their color unimpaired. They will, however, be somewhat diminished 25 in intensity in proportion to the opaqueness of the white material. This may be demonstrated by viewing a thin sheet of white paper before the light and placing papers of various colors between the white paper 30 and the light.

While a specific form of the improvement has been described and illustrated herein, it is desired understood that the same 35 may be varied, within the scope of the appended claims, without departing from the spirit of the invention.

Having thus described the invention, what I claim and desire secured by Letters Patent is:—

40 1. Indicating means comprising a plate

having cut out characters; a translucent plate behind the former plate, said translucent plate being white on the front face and colored on the rear face and means for illuminating the rear of said translucent 45 plate.

2. Indicating means comprising a plate having cut-out characters; a light source; a translucent medium arranged between said light source and said plate, said translucent 50 medium being colored on the side toward said light source so as to permit the passage of colored light rays from said source through said plate and colored on the side toward said plate to reflect light rays of a 55 color differing from those transmitted therethrough.

3. Indicating means for an automobile comprising, a cut out plate bearing the name of the automobile; a translucent plate behind said cut out plate, said translucent plate being white on the face toward said cut out plate and colored on the opposite face to correspond to the color of said automobile, and means for illuminating the colored face of said translucent plate.

4. Indicating means for an automobile comprising an opaque plate with cut out characters showing the license number and name of said automobile; a translucent plate 70 arranged behind said opaque plate, said translucent plate being white on the face toward said opaque plate and colored on the opposite face behind said license number red and behind said name to correspond to the 75 color of said automobile, and means for illuminating the colored face of said translucent plate.

In testimony whereof I affix my signature.
PAUL A. JOHNSON.

Certificate of Correction.

It is hereby certified that in Letters Patent No. 1,471,837, granted October 23, 1923, upon the application of Paul A. Johnson, of Denver, Colorado, for an improvement in "Illuminated Indicators," an error appears in the printed specification requiring correction as follows: In the drawing Fig. 5, for the reference numeral "13" read 25; and that the said Letters Patent should be read with this correction therein that the same may conform to the record of the case in the Patent Office.

Signed and sealed this 5th day of February, A. D., 1924.
